COMBINATION NUT RUNNING AND SETTING TOOL

Ernest H. Shaff, Spring Lake, Mich., assignor, by
mesne assignments, to Keller Tool Company,
Grand Haven, Mich., a corporation of Michigan

Application June 10, 1947, Serial No. 753,598

18 Claims. (Cl. 73—139)

1

The present invention pertains to portable tools for running and setting screw-threaded fastening elements such as nuts, bolts and screws.

Generally stated, it is an object of the invention to provide a tool of the above general character by which such fastening elements may be run by power actuation of the tool and set by manual operation thereof and which includes means to indicate attainment of the desired degree of tightness.

Another object is to provide a combined nut-runner and torque wrench of the character set forth above wherein conversion from power to manual operation is incidental to the shutting off of the power.

The objects of the invention thus generally set forth together with other and ancillary advantages are attained by the construction and arrangement shown by way of illustration in the accompanying drawings, in which:

Figure 1 is a plan view of the combined nut-runner and torque wrench.

Fig. 2 is a sectional side elevation taken substantially in the plane of line 2—2 in Fig. 1.

Fig. 3 is a sectional elevation taken substantially in the plane of line 3—3 in Fig. 2 and showing the relationship of the elements when the tool is power actuated.

Fig. 4 is a sectional elevation substantially in the plane of line 4—4 in Fig. 2.

Fig. 5 is a vertical section illustrating the relationship of the tool elements under manual application of force to the tool.

Fig. 6 is a sectional elevation taken substantially in the plane of line 3—3 in Fig. 1 and showing component relationship for forward manual operation of the tool.

Fig. 7 is a sectional elevation taken substantially in the plane of line 3—3 in Fig. 1 and showing component relationship for reverse manual operation of the tool.

Fig. 8 is an end elevation partly in section taken substantially in the plane of line 8—8 in Fig. 5.

Fig. 9 is a plan view of a modified form of the combined nut runner and torque wrench also embodying the present invention.

Fig. 10 is a sectional side elevation taken substantially in the plane of line 10—10 in Fig. 9.

Fig. 11 is a sectional elevation taken substantially in the plane of line 11—11 in Fig. 10.

Fig. 12 is a sectional elevation taken substantially in the plane of line 12—12 in Fig. 10.

While the invention is susceptible of various modifications and alternative constructions, there is shown in the drawings and will herein be de-

2

scribed in detail the preferred embodiments, but it is to be understood that it is not thereby intended to limit the invention to the form disclosed, but it is intended to cover all modifications and alternative constructions falling within the spirit and scope of the invention as expressed in the appended claims.

In carrying out my invention I provide a portable tool comprising a power unit 10 embodying 10 a rotary motor 11 enclosed within a casing 12, and a tool head 13 connected with the power unit in laterally spaced relation thereto and having a driven shaft 14 connected with the motor of the power unit by a drive shaft 15. The driven shaft 15 is constructed for the mounting of a suitable adaptor varying in accordance with the character of the threaded element to be driven, and is disposed at right angles to the drive shaft. In the operation of the tool in "running" a screw, nut or other threaded element, the driven shaft is rotated continuously, but in order that the tool can be used for tightening or setting the threaded element manually, a disengageable connection 16 is provided between the driven shaft and the tool head so constructed and arranged as to be ineffective when the shaft is driven by the motor but operative when the motor is idle to permit of the application of a rotative force to the tool head and therefore to the driven shaft by the application of a lateral manual force to the power unit. Finally, I provide indicator means 17 responsive to relative lateral movement between the tool head and the power unit to indicate to the operator the degree of torque applied manually to the driven shaft, the drive shaft being made flexible to permit of such relative movement.

In the present embodiment shown in Figs. 1 to 8, the drive motor 11 is of the reversible rotary fluid pressure actuated type and includes a rotor 40 18 fast on a spindle 19. The latter is journaled adjacent its forward end in a bearing 20 which in turn is held in a frame collar 21 made stationary with respect to the casing 12 of the power unit. The outer end of the casing, herein the right end, terminates in a handle 22, and pressure fluid for the motor is supplied by way of an inlet fitting 23 on the outer end of the handle. The admission of pressure fluid to the motor is controlled by a reversing valve assembly 25.

50 In the instant embodiment, the tool head 13 includes a housing 30 of generally cylindrical form having a chamber 31 therein which is closed at its top by a plug 32. The driven shaft 14 is journaled intermediate its ends in a bore 33 in the housing 30 and is supported at its upper

end in a bearing 34, the latter being held in the plug 32. The lower end 14a of the driven shaft extends beyond the housing 30 and is fashioned to receive a suitable adaptor, such for example, as a socket 35 illustrated in dot-dash lines in Fig. 2. Positioned within the chamber, concentric with the driven shaft 14 and secured thereto by a key 36 is a bevel gear 37. Projecting at right angles from the housing 30 and preferably made integral therewith is a boss 38 having a bore 39 therein which extends coaxially with the longitudinal axis of the tool. The tool head 13 is connected with the power unit through the medium of a tube 40 one end of which is secured in the bore 39 by set screw 39a and the other end thereof if fixed within the stationary frame collar 21 of the power unit. Extending coaxially within the tube 40 and connecting the motor of the power unit with the tool head is the drive shaft 15 which is conveniently joined at one end to the motor spindle 19 by means of a tongue and groove joint 41. The other or terminal end of the drive shaft, projects beyond the supporting tube 40, and carries a bevel pinion 42 which may be made integral with the drive shaft 15. The teeth of the bevel pinion 42 are in mesh with those of the bevel gear 37 thus completing the driving connection between the motor of the power unit and the driven shaft 14 so that in the operation of the tool in "running" a fastening element the driven shaft is rotated continuously in one direction or the other.

So that the driven shaft 14 may be rotated by the application of a lateral manual force to the motor unit in order to finally tighten or set a fastening element, the disengageable connection 16 is provided between the tool head housing 30 and the driven shaft 14. In the present instance this connection is of the pawl and ratchet type. It includes a pawl 43 positioned in spaced relation to the axis of the driven shaft 14 and beneath the bevel gear 37. The bevel gear, in the present instance, is utilized to provide a ratchet disk rigid with the driven shaft 14. Thus it is provided with a series of radially extending notches 44 in its lower face.

The pawl 43 is rigid with the upper end of a plunger 45 which serves as an actuator therefor. The latter has a sliding fit in a bore or recess 46 provided in the chamber 31 and in communication therewith. A spring 47 tends to urge the plunger 45 upwardly to carry the pawl into engagement with the notches 44 of the ratchet disk. To provide ratchet action in either direction of operation, the plunger can be rotated through 180° by means of a fingerpiece 48 extending radially therefrom so that the direction of presentation of the flat face of the pawl to the notch walls can be reversed.

As above indicated, the connection 16 is rendered ineffective when power is applied to the motor 11 to drive the shaft 14. This is accomplished in the present instance by fluid pressure inasmuch as the motor employed is of the fluid pressure type. To this end, the chamber 31 is connected to the fluid pressure supply. Thus a passage 49 extends from the tool head chamber 31 longitudinally through the drive shaft 15 and the motor spindle 19. The manner of supplying air to the passage 49 will be more fully explained in the modified form hereinafter described.

It will be observed that air delivered to the tool head chamber 31 is free to pass around

the bevel gear 37 and act on the upper surface of the plunger 45 to force it downwardly against the action of the spring 47. Thus as an incident to the application of the motive power to the motor, the ratchet pawl 43 is forced out of engagement with the bevel gear notches 44. Conversely, when the fastening element has become tight and the power is shut off, pressure in the tool head chamber 31 is released, and the spring 47 will urge the plunger 45 upwardly so that the ratchet pawl 43 engages one of the notches 44, thus rendering the connection 16 effective for tightening purposes. In this operation lateral force in the appropriate direction is applied manually to the handle 22, which together with the casing 12, shaft 15 and tube 40 serves as a lever for applying a strong rotative force to the driven shaft 14.

In many uses of the tool, as for example, in the installation of a cylinder head, it is desirable that all of the fastening elements be set to the same degree of tightness. To this end, the connection between the power unit and the tool head is made flexible so that upon application of lateral manual force to finally set a fastener there will be an appreciable relative displacement between the tool head 13 and power unit 10 capable of utilization in the actuation of the indicator means 17.

In the present instance, the tube 40 is made of resilient material such, for example, as spring steel, and the shaft is made flexible. As illustrated, the latter comprises a plurality of interengaging sections 52 and 53, the latter forming the terminal end of the shaft which projects into the chamber 31. The sections 52 are formed with enlarged end portions 54 and 55 which serve as bearing surfaces to support the drive shaft 15 in the tube 40 and as reinforcement for the tube when it is bent under manual application of force to the tool. To join the shaft sections, the adjacent end portions thereof are provided with diametrical slots 56 and tongues 57. Since the forward end of the tube 40 is rigidly secured within the bore 39 of the tool head boss 38, there will be no bending of this portion of the tube. Accordingly, the terminal section 53 of the drive shaft 15 is of the same diameter throughout its length.

In the instant embodiment, the means provided to indicate the amount of displacement of the power unit relative to the tool head, in finally setting a fastening element, includes a tubular housing 60 which is fixed to the tool head boss 38 and which extends toward the power unit 10 coaxially of the tube 40 and drive shaft 15. The rear portion of this housing is flattened and outwardly flared and the upper end thereof terminates in a gear segment or rack 61. Positioned on the forward end of the motor casing 12 is a cap 62 which is supported on needle bearing 63 carried on the frame collar 21 (Fig. 2). The forward end of the cap 62 is fashioned into a pinion gear 64 which is coaxial with the tube 40 and drive shaft 15, and the teeth thereof are in mesh with those of the rack 61. The rear end portion 65 of the cap is enlarged and extends over the forward end of the motor casing 12.

Since the tubular housing 60 is rigid with the tool head, it will not be displaced upon manual application of force to the power unit. However, the movement of the power unit with respect to the tubular housing 60 will cause the cap 62 on the forward end of the motor casing 70 to be rotated and the amount of its angular

movement will be proportional to the amount of lateral displacement of the tube and shaft from normal position. Thus the cap can be calibrated to indicate the amount of such displacement, and for this purpose the enlarged rear end portion 65 of the cap 62 is provided with a circumferentially arranged series of markings constituting a scale 66, which when taken in conjunction with a fixed reference point on the motor casing 12, herein shown in the form of a pointer 67, indicates directly the amount of displacement. The calibration is arranged so that when there is no displacement from normal position, the scale will register zero and displacement in either direction is shown by correspondingly increasing indications in such direction.

The tubular housing not only serves as an element of the indicator means, but also provides protection for the tube 40 and drive shaft 15.

In the embodiment shown in Figs. 9 to 12, the drive motor 80 is of the fluid pressure actuated type having rotation in one direction only. It includes a rotor 81 fast on a spindle 82 and disposed within a chamber 83 in the motor casing 84. The spindle extends through holes 85 and 86 in frame disks 87 and 88 and is journaled adjacent its ends in bearings 89 and 90 which in turn are held in the frame disks. One end of the spindle 82 is connected to a drive shaft 91 disposed within a tube 92, which connects the power unit and the tool head in spaced relation. Pressure fluid for the motor is supplied by way of a passage 93 and admission of pressure fluid to the motor is controlled by a simple push button valve 94.

In this embodiment, the tool head includes a housing 100 of generally cylindrical form having a chamber 101 therein which is closed at its top by a plug fitting 102. A driven shaft 103 is journaled in the housing and carries a bevel gear 104 meshing with a bevel pinion 105 on the drive shaft 91.

So that the driven shaft 103 may be rotated by the application of a lateral manual force to the motor unit to set a fastening element, a disengageable pawl and ratchet connection is provided between the tool head housing 100 and the driven shaft 103 including a pawl 106 engageable with a peripherally arranged series of notches 107 in the bevel gear 104. The pawl 106 is rigid with an actuating plunger 108 urged inwardly by a spring 109.

To render the connection ineffective when power is applied to the motor 80 to drive the shaft 103 the plunger 108 is forced outwardly thereby holding the pawl 106 out of engagement with the notches 107 of the bevel gear 104. As in the preceding embodiment, the plunger is forced outwardly by fluid pressure, and to this end a passage 110 extends from the tool head chamber 101 longitudinally through the drive shaft 91 and the motor spindle 82 and communicates with a chamber 111 in the motor casing 84 beyond the motor spindle bearing 89. When pressure fluid is admitted to the motor by the operation of the valve 94 air from the motor chamber 83 passes between the end of the rotor 81 and the frame disk 87 and thence rearwardly along the spindle 82 and through the bearing 89 to the chamber 111. Thus when the valve 94 is operated to actuate the motor, pressure is immediately supplied to the tool head chamber 101, and such pressure being exerted around the bevel gear 104, operates on the inner surface of the plunger 108 to force it outwardly against the

action of the spring 109 thereby holding the ratchet pawl 106 out of engagement with the notches 107 of the bevel gear 104. As previously set forth, when a fastening element has become tight upon running by the power actuated tool, the power is shut off, and as an incident to the interruption of the power, pressure is removed from the tool head chamber and the spring 109 will urge the plunger 108 inwardly so that the ratchet pawl 106 engages one of the notches 107 thereby rendering the connection between the tool head housing 100 and the driven shaft 103 operative when the motor 80 is idle and latching the driven shaft 103 with respect to the tool head.

In the instant embodiment the means provided to indicate the amount of displacement of the power unit, tube and shaft upon manual application of force to finally set a fastener includes a plate 115 which is fixed to the tool head by means of cap screws 116 and which extends toward the power unit in overlying relation to the tube 92 and shaft 91. On the rear end portion of this plate is formed a gear segment or rack 117 for engagement with a pinion gear 118 fashioned on the forward end of a cap 119 which is rotatably mounted on the forward end of the power unit. The longitudinal side edges of the plate 115 are turned downwardly to provide additional strength. The operation of the instant indicator means is, in general, the same as that set forth for the first embodiment disclosed. However, in the instant embodiment the rear end portion of the cap 119 carries but a single indicator mark 120 and a scale band 121 having a peripherally arranged series of scale markings is fixed to the motor casing 84 thus providing the movable and fixed elements of the indicator means for measuring the amount of torque produced upon application of lateral manual force for setting a fastener.

To permit reverse operation in this modified form of the invention, the tool is so constructed that either end of the driven shaft 103 can receive and support a suitable adaptor to accommodate the fastening element to be driven. In the present instance, the driven shaft 103 is provided with an axially extending square passage 122 within which is a correspondingly shaped shank 123, the latter being fashioned for the mounting of a suitable adaptor varying in accordance with the character of the fastening element to be driven. As illustrated in Fig. 10, the shank 123 is adapted to occupy two alternative positions axially with respect to the driven shaft 103, so that an adaptor can be mounted on either of its ends. To hold the shank in either of its alternative positions, grooves 124 and 125 are provided in the shaft passage 122 for the reception of pins 126 and 127 projecting from the shank 123. As shown, the pins 126 and 127 are urged outwardly for engagement in the grooves 124 and 125 by resilient inserts 128 and 129 positioned in recesses provided therefor in the ends of the shank 123. Thus operation of the tool in either direction may be obtained by merely presenting to the work that end of the driven shaft which is rotated in the desired direction. It can be seen therefore that a unidirectional motor can be utilized to actuate the tool and by the same token the pawl and ratchet mechanism can also be constructed for unidirectional operation. The construction of the tool is thus simplified and its cost of manufacture reduced.

I claim as my invention:

1. A tool comprising, in combination, a power unit including a motor having a drive shaft, a tool head connected with the power unit in spaced relation thereto and having a driven shaft journaled therein operatively connected to said drive shaft, a normally engaged connection between said driven shaft and said tool head whereby the head and driven shaft can be rotated together by application of lateral manual force to said power unit, and an element operatively associated with said connection actuated in response to the application of power to said motor for disengaging the connection.

2. A tool comprising, in combination, a power unit including a motor and a drive shaft, a tool head connected with the power unit in spaced relation thereto and having a driven shaft journaled therein geared to said drive shaft, and means including a locking member providing a disengageable latching connection between said driven shaft and said tool head, said locking member being automatically rendered ineffective in response to motor actuation of said driven shaft and made effective in response to the interruption of power to said motor so that said tool head and driven shaft can be rotated together by application of lateral manual force to the power unit.

3. A tool comprising, in combination, a power unit including a motor with a manually operable control device therefor, a drive shaft, a tool head connected with the power unit in spaced relation thereto and having a driven shaft journaled therein geared to said drive shaft, a ratchet disk secured to said driven shaft, a pawl operatively associated with said tool head, spring means normally urging the pawl into engagement with the disk, and means including an element actuated in response to the actuation of said control device to hold said pawl out of engagement with said ratchet disk when the tool is power actuated, said pawl being urged by said spring means into engagement with the disk upon interruption of power to the tool whereby said tool head and driven shaft can be rotated together by application of lateral manual force to the power unit.

4. A tool for connection with a pressure fluid supply comprising, in combination, a power unit having a fluid pressure actuated motor, a drive shaft rotated by said motor, a tool head, a tube enclosing said drive shaft and connecting said tool head and power unit in spaced relation, a driven shaft journaled in said tool head and geared to said drive shaft, a member supported in said tool head normally engaging said driven shaft to latch the driven shaft against rotation relative to the head whereby said tool head and driven shaft can be rotated as a unit by application of lateral manual force to said power unit, and an element operatively associated with said member and having connection with the fluid pressure supply for automatically shifting said member out of engagement with the driven shaft upon application of pressure fluid to said motor whereby to free the driven shaft for rotation in the head.

5. A tool comprising, in combination, a power unit including a reversible motor having a drive shaft, a tool head connected with the power unit in spaced relation thereto and having a driven shaft journaled therein geared to said drive shaft, a ratchet disk secured to the driven shaft, a pawl normally in engagement with said disk

5 means to reverse said pawl with respect to said disk whereby said driven shaft can be latched with respect to said tool head to permit rotation in alternative directions of said shaft and tool head as a unit upon application of lateral manual force.

6. A combined nut runner and torque wrench comprising, in combination, a power unit having a flexible drive shaft, a tool head, a resilient tube supporting said tool head on said power unit in spaced relation thereto, a driven shaft journaled in said tool head and operatively connected to said drive shaft, a disengageable connection between said driven shaft and said tool head operative to permit said tool head and driven shaft to be rotated together by application of lateral manual force to the power unit, and an indicator responsive to relative displacement between said power unit and said tool head upon application of said force whereby the amount of torque produced can be measured.

7. A combined nut runner and torque wrench comprising, in combination, a power unit including a casing, a motor within the casing having a drive shaft extending beyond said casing, a tool head, a tube enclosing said drive shaft and connecting said tool head and said casing in spaced relation, a driven shaft journaled in said tool head and geared to said drive shaft, a disengageable connection between said driven shaft and said tool head operative to permit said head and shaft to be rotated by application of lateral manual force to said casing while using said casing, shaft and tube as a lever, and indicator means responsive to relative lateral movement between said tool head and said power unit upon application of such force, said drive shaft and tube being made flexible to permit of such relative movement.

8. A combined nut runner and torque wrench comprising, in combination, a power unit including a casing, a motor within the casing having a drive shaft extending beyond said casing, a tool head, a tube enclosing said drive shaft and connecting said tool head and said casing, a driven shaft journaled in said tool head and geared to said drive shaft, a disengageable connection between said driven shaft and said tool head operative to permit rotation of said head and shaft by application of lateral manual force to said power unit, and indicator means responsive to relative lateral movement between said tool head and said power unit upon application of such force, said tube being resilient and said drive shaft comprising a plurality of sections loosely coupled together to permit of such relative movement.

9. A tool comprising, in combination, a power unit including a motor having a drive shaft, a tool head connected with said power unit in spaced relation thereto, a driven shaft journaled in said tool head, a first gear element secured to said drive shaft, a second gear element secured to said driven shaft in mesh with said first element and having notches therein, a plunger in said head adjacent said second gear element and having a ratchet pawl thereon for engagement in said notches, a spring urging said plunger and pawl toward said second gear element, and means responsive to the actuation of said motor for shifting said plunger to hold said

pawl out of engagement with said notches against the action of said spring when said driven shaft is power actuated.

10. In a tool for connection with a fluid pressure supply and having a casing, the combination comprising a fluid pressure operated motor within said casing and having a drive shaft extending therefrom, a tool head having a chamber therein, a tube enclosing said drive shaft and connecting said tool head and said casing in spaced relation, a driven shaft journaled in said chamber and connected with said drive shaft, a ratchet disk secured to said driven shaft within said chamber, a plunger extending into said chamber and having a ratchet pawl thereon for engagement with said disk, a spring urging said plunger toward said disk, and means connecting said chamber with the fluid pressure supply including a passage extending axially of said drive shaft, whereby said plunger is forced away from said disk by fluid pressure when said motor is operated and is forced toward said disk by the action of said spring upon interruption of the fluid pressure supply so that said pawl engages said disk to latch said driven shaft and tool head together to permit rotation thereof by application of lateral manual force to said casing.

11. A combined nut runner and torque wrench comprising, in combination, a power unit having a casing, a motor within said casing having a flexible drive shaft extending therefrom, a tool head, a resilient tube enclosing said drive shaft and connecting said tool head and said power unit in spaced relation, a driven shaft journaled in said head and geared to said drive shaft, a disengageable connection between said tool head and said driven shaft operative to permit rotation of said tool head and driven shaft by application of lateral manual force to said power unit, and indicator means including a first element rigid with said tool head and a second element supported on said casing, said indicator means being operative to measure the amount of relative displacement between said head and said casing and thereby indicate the amount of torque produced by application of said force.

12. A combined nut runner and torque wrench comprising, in combination, a power unit having a casing, a motor within said casing having a flexible drive shaft extending therefrom, a tool head, a resilient tube enclosing said drive shaft and connecting said tool head and said power unit in spaced relation, a driven shaft journaled in said head and geared to said drive shaft, a disengageable connection between said tool head and said driven shaft operative to permit rotation of said tool head and driven shaft by application of lateral manual force to said power unit, and indicator means including a tubular member rigid with said tool head extending coaxially with respect to said flexible drive shaft and tube and having a rack gear segment on its rear end portion, and a cap rotatably mounted on said casing having its forward end portion fashioned into a pinion gear in mesh with said rack gear segment and having a scale on its rear end portion, said cap being rotated with respect to said casing upon relative displacement of said tool head and casing upon application of said force whereby the amount of force applied can be measured.

13. A combined nut runner and torque wrench comprising, in combination, a power unit having a casing, a motor within said casing having a flexible drive shaft extending therefrom, a tool

head, a resilient tube enclosing said drive shaft and connecting said tool head and said power unit in spaced relation, a driven shaft journaled in said head and geared to said drive shaft, a disengageable connection between said tool head and said driven shaft operative to permit rotation of said tool head and driven shaft by application of lateral manual force to said power unit, and indicator means including a tubular member rigid with said tool head extending coaxially with respect to said flexible drive shaft and tube and having a rack gear segment on its rear end portion, and a cap rotatably mounted on said casing having its forward end portion fashioned into a pinion gear in mesh with said rack gear segment and having a scale on its rear end portion, said cap being rotated with respect to said casing upon relative displacement of said tool head and casing upon application of said force.

14. A combined nut runner and torque wrench comprising, in combination, a power unit having a casing, a motor within said casing having a flexible drive shaft, a tool head, a resilient tube enclosing said drive shaft and connecting said tool head and said power unit in spaced relation, a driven shaft journaled in said head and geared to said drive shaft, a disengageable connection between said tool head and said driven shaft operative to permit rotation of said tool head and driven shaft by application of lateral manual force to said power unit, and indicator means including a plate rigid with said tool head and extending toward said power unit in overlying relation to said tube and drive shaft and having a rack gear segment on its rear end portion, a cap rotatably mounted on said casing having its forward end portion fashioned into a pinion gear in mesh with said rack gear segment and having a reference mark thereon, and a fixed scale on said casing adjacent said cap, said cap being rotated with respect to said fixed scale upon relative displacement of said tool head and said casing upon application of said force whereby the amount of force applied can be measured.

15. A tool comprising, in combination, a power unit having a drive shaft, a tool head, a tube journaling said drive shaft and connecting said tool head and power unit in spaced relation, a driven shaft operatively connected with said drive shaft and journaled in said tool head, a member supported in said tool head and coaxial with said driven shaft to hold the driven shaft against rotation relative to the head, yieldable means normally urging said member into holding engagement with said driven shaft so that said tool head and driven shaft can be rotated together as a unit by application of lateral manual force to said power unit, means responsive to the application of power to the tool for automatically shifting said member against the action of said yieldable means and out of engagement with said driven shaft to free the driven shaft for rotation in the head.

16. A tool comprising, in combination, a power unit including a motor and a drive shaft, a tool head connected with the power unit in spaced relation thereto and having a driven shaft journaled therein geared to said drive shaft, and pawl and ratchet members interposed between said driven shaft and said tool head, one of said members being responsive to the application of power to the motor so as to be ineffective when said driven shaft is motor actuated so as to free said driven shaft for rotation with respect to said

11

tool head, and means including an element operative in response to the interruption of power to said motor to effect engagement between said pawl and ratchet members whereby said tool head and driven shaft can be rotated together by application of lateral manual force to the power unit.

17. In a tool having a power unit including a motor with a drive shaft, the combination of a tool head having a driven shaft journaled therein adapted to be driven by the drive shaft, means providing a handle extending laterally from said tool head in a generally radial direction with respect to said driven shaft, a member supported in said tool head and coacting with said driven shaft to hold the driven shaft against rotation relative to said tool head, yieldable means normally urging said member into holding engagement with said driven shaft whereby said tool head and said driven shaft can be rotated as a unit by application of lateral manual force to said handle, and means responsive to the application of power to the tool for automatically shifting said member against the action of said yieldable means and out of engagement with the driven shaft to free the same for rotation with respect to the tool head by said power unit.

18. In a power actuated tool, the combination of a tool head, a driven shaft journaled in said tool head, means defining a handle carried by said tool head and extending laterally therefrom

12

in a generally radial direction with respect to said driven shaft, and means including a locking member providing a disengageable latching connection between said driven shaft and said tool head, said locking member being responsive to the application of power to the tool so as to be ineffective whereby said shaft can be power driven, said locking member being effective in response to the interruption of power to the tool so that said tool head and driven shaft can be rotated together by application of lateral manual force to the handle.
